(57) **CLAIM**

The ornamental design for a car configured ladder cap, as shown and described.

DESCRIPTION

FIG. 1 is a top right front perspective view of the ladder cap of the invention with the ladder shown in phantom;

FIG. 2 is a top right side rear perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side elevation view being a mirror image of the left side elevation view thereof.

The broken lines are for illustrative purposes only and form no part of the claimed design.
